UNITED STATES PATENT OFFICE.

RICHARD W. OWEN, JR., OF CHICAGO, ILLINOIS, ASSIGNOR, BY MESNE ASSIGNMENTS, TO THE INDESTRUCTO TRUNK CORPORATION, OF MISHAWAKA, INDIANA, A CORPORATION OF INDIANA.

WARDROBE-TRUNK-DRAWER RETAINER.

Application filed November 8, 1920. Serial No. 422,733.

To all whom it may concern:

Be it known that I, RICHARD W. OWEN, Jr., a citizen of the United States, residing at Chicago, in the county of Cook and State 5 of Illinois, have invented certain new and useful Improvements in Wardrobe-Trunk-Drawer Retainers, of which the following is a specification.

My invention relates to improvements in 10 wardrobe trunk drawer retainers, and it more especially comprises the features pointed out in the annexed claims.

The purpose of my invention is to provide 15 a self-contained drawer retainer that will effectively hold the drawers of wardrobe trunks in place against shifting while in transit without employing complicated parts; that will be readily adapted to existing trunks without any changes in the trunk 20 structure whatever; that is also specially adaptable to new trunks in the process of manufacture; that is extremely simple to make and as simple to use.

With these and other objects in view, I 25 illustrate in the accompanying drawing such instances of adaptation as will disclose the broad underlying principles of the invention without limiting myself to the specific details which are shown in the drawing and 30 are described herein.

Fig. 1 is a front elevation of the drawer portion of a wardrobe trunk, with the retainer in position, adapted to an existing trunk in which the drawer lock is centrally placed.

Fig. 2 is a side elevation of Fig. 1, partly in section.

Fig. 3 is a detached front elevation of a modified form of the retainer.

Fig. 4 is a front elevation of a retainer placed centrally of a drawer and the key-lock to one side.

Fig. 5 is an enlarged elevation of the retainer shown in side elevation with the adjacent drawer parts in section.

Fig. 6 is a detached elevation showing a top drawer with a positioning notch in the upper edge of the drawer front.

In practically carrying out my invention 50 I make the retainer a removable element that can be taken away from the drawers entirely. When a trunk is opened the retainer can be hung from the side of the top drawer until the trunk is to be closed. The

drawer side of a wardrobe trunk is represented by 1. In this there is an upper drawer 2 provided with any desired kind of key-lock 3. A bottom drawer 11 is also provided as well as intermediate drawers 12.

Between the bottom drawer 11 and the one immediately above a partition 6 is placed. On this a slotted plate 5 is secured. It has a slot 17 through which the lower end 7 of the retainer bars 4 and 13 passes. The upper end of the retainer may be forked in any desired manner, as shown in Figures 1 and 3 or in any other way. In Fig. 1 the curved part 9 has hook ends 8 formed by which the whole retainer is suspended from the upper edge of the drawer front of the top drawer 2. In Fig. 3 the fork takes the shape of the letter V the two arms of the "letter" being indicated by 10. At the junction of these arms they are attached to the straight stem 4. They have hook ends 14 which serve the same purpose as ends 8.

The single bar 13 combined with its hook-end 15 forms the simplest type of retainer. This is usually applied to new trunks in the process of manufacture, and in such cases 80 the lock 3 is placed just to one side to clear the bar 13. The hook ends 8, 14, and 15 may rest in positioning notches 16 formed in the upper edge of the front of the top drawer. As a matter of fact there is usually 85 enough clearance between the upper edge of the drawer 2 and the inner edge of the trunk to admit the thin portion of the hook ends without the use of notches 16. An obvious advantage of the notches is to assist the 90 slot 17 in plate 5 to keep the retainers approximately central of all the drawers.

The operation of the retainer is simplicity itself. After the drawers are all closed except the top one, the curved bottom end 7 of the bar 4 is slipped through the opening 17 of plate 5, which plate is secured to the shelf 6, and then the end 15 or ends 8 or 14 are hooked over the top front edge of the uppermost drawer. The top drawer is 100 now closed and locked. In this way the bar 4 or bar 13 passes in front of all the drawers 2 and 12 and in addition projects in front of the lower drawer 11. As soon as the top drawer is locked none of the other drawers 105 can be opened wilfully or be misplaced while the trunk is in transit. There is also secured a very desirable feature through the

use of these retainers, in that the drawers can all be locked without closing the entire trunk to secure desired privacy and prevent the contents of the drawers being tampered with while the trunk stands open.

I am aware that various attempts have been made to effect drawer locking devices of one type or another, but I do not believe any device having the efficiency of my 10 present device has been made heretofore. There have also been made various retaining devices which are attached to the other half of the trunk, but these only hold the drawers in place while the trunk is closed, 15 leaving them accessible to any prowler that may happen around, except the top drawer which is usually locked in trunks of this type. The other drawers are of course entirely unprotected.

20 From the description it is quite obvious that the reason the retainers cannot be removed as long as the top drawer is locked or is unopened lies in the fact that the hook ends pass under the trunk edge and in consequence cannot be raised, thus effectually retaining and at the same time locking all 25 the other drawers.

What I claim is,

1. In drawer retaining and locking devices, a series of drawers, a removable rigid 30 member adapted to pass in front of the drawers to be held, means for holding the lower end of said member against sidewise movement, and means comprising a hook on the upper end of said member to pass over and down inside one of the drawers, said drawer being locked to retain said member in locking position by its interposition between the drawer and its support.

2. In drawer retaining and locking devices, a suitable walled compartment, a series of drawers therefor, a removable rigid member adapted to pass in front of the drawers to be held, means for holding the lower end of said member against side-wise movement, and means comprising a hook on the said member to pass over and down inside of one of the drawer fronts, said drawer being locked to retain said member in locking position by the interposition of its hook between the drawer and a wall of said compartment.

In testimony whereof I affix my signature.
RICHARD W. OWEN, JR.
